UNITED STATES PATENT OFFICE.

FREDERICK WILLIAM LANCHESTER, OF LONDON, ENGLAND.

AEROPLANE AND APPARATUS FOR LAUNCHING AND RECEIVING SAME.

1,311,700.

Specification of Letters Patent.

Patented July 29, 1919.

Application filed January 18, 1919. Serial No. 271,934.

To all whom it may concern:

Be it known that I, FREDERICK WILLIAM LANCHESTER, a subject of the King of Great Britain and Ireland, and residing at 41 Bedford Square, London, W. C. 1, England, have invented certain new and useful Improvements in Aeroplanes and Apparatus for Launching and Receiving Same, of which the following is a specification.

10 The present invention relates to improvements in aeroplanes and apparatus for launching and receiving same, and has for its object to permit of the launching and receiving of aeroplanes by vessels at sea, and 15 otherwise under unfavorable conditions of landing and when accommodation of the ordinary kind is not available, such, as, for example, on small islets or rocky coasts.

The present invention consists in apparatus for launching and receiving aeroplanes comprising a multiple tight-rope track adapted to directly support them and a counter-part or complementary provision on the fuselage or wing members of the 25 aeroplane comprising laterally arranged rails or runners forming continuous transverse bearers extending the length of the span of the wing structure.

The present invention further consists in 30 a means or mechanism embodied in and actuated from the aeroplane for gripping one or more of the tight-ropes aforesaid to act as a brake to bring the aeroplane rapidly to rest.

35 The present invention further consists in the application of a multiple tight-rope launching and receiving apparatus to sea-going vessels comprising a multiple tight-rope track mounted on folding outriggers 40 by means of which the track may be housed or shipped when not required.

The present invention further consists in the improvements in aeroplanes and apparatus for launching and receiving same 45 hereafter described.

The drawings herewith illustrate one mode of carrying the invention into effect.

Figure 1 is an elevation, and

50 Fig. 2 is a plan showing a pair of multiple rope tracks as fitted to a ship, one track being shown housed close to the side of the ship, the other track being shown outswung in its operative position.

Fig. 3 is an elevation, and

55 Fig. 4 is plan of one of the outriggers.

Fig. 5 is a view of one of the cable swivel posts and cable tensioning device.

Fig. 6 is a side elevation showing the two transverse bearers or runners fitting below the fuselage of an aeroplane.

Fig. 7 is an end-way elevation showing one of the said bearers or runners.

Fig. 8 is a view of the guiding and braking device.

Fig. 9 is an end view of one of the outriggers.

As concerns the track for launching and receiving aeroplanes as applied to a sea-going vessel, two outriggers 1 are provided consisting of brackets furnished with spar 70 extensions, the said brackets being pivoted on vertical axes 2 to lugs 3 fixed to the side of the vessel and adapted to be swung out at right angles when in use or to be housed parallel or nearly parallel to the side of the 75 vessel when shipped. A number of tight-ropes 4, conveniently some dozen or more, are carried by the outriggers aforesaid. Each tight-rope, stretching from outrigger to outrigger, is carried by a pair of swivel 80 heads 5, one such head being provided on either outrigger for each rope. A suitable construction of swivel head is as follows. A vertical shaft 6 is mounted in journals in the outrigger and this tubular shaft has a 85 continuation 7 at its upper extremity of quadrant form and furnished with a groove in which the tight-rope is constrained to rest. This continuation may be considered as an extension of the shaft 6 bent to an 90 easy radius through a right angle, a portion 8 of the bend being cut away to expose a bore. The tight-rope is threaded through the bore and is furnished at the lower extremity with a screw 9 or other tightening 95 device, which seats itself under tension in the bored end of the quadrant continuation. The axes of the swivel heads are parallel to one another and parallel to the outrigger 100 mountings so that when the outriggers are housed, the whole combination forms a multiple parallelogram linkwork, adapted to lie snugly against the side of the vessel.

A number of chains or cables 10, which act as guy ropes, are attached to each outrigger and are led around suitable guide pulleys on board ship. The chains may be connected from one outrigger to the other on board ship. Tensioning devices are provided for the said chains or cables and the 110

tension imposed thereon determines the aggregate tension imposed on the tight-ropes of the track. One of the said cables is led round a windlass or the like. By turning 5 the windlass the outriggers and track are moved from the "housed" to the "operative" position, or vice versa, when desired.

In another arrangement the outrigger tensioning chains or the like are connected at 10 bow and stern respectively to hydraulic controlling and operating gears.

As concerns the aeroplane, the lower wing members are arranged flush with or somewhat below the floor of the fuselage. The 15 present familiar forms of landing chassis are abolished and in place of two transverse bearers or runners 14 are fitted at or near the leading and trailing edges of the lower wing members and continuous from right 20 to left, the said runners being of metal or hard wood and adapted to bear on the multiple tight-rope track on the aeroplane alighting. In one (or both) of the runners at or near its center and beneath the fuse- 25 lage a V-shaped notch or gate 15 is formed, as shown in Fig. 8, and a counter-part V-shaped brake block 16 is correspondingly arranged with vertical sliding motion controlled by the pilot. When alighting the 30 brake block is set in its lowermost position and one or other of the tight-ropes 4 forming the track is caught in the V-groove between one of the fixed flanks of same and the brake block aforesaid. By raising the 35 brake block by means of mechanism provided the pilot can bring any required degree of grip to bear on the particular rope engaged and thereby exert any desired degree of braking effort. In order to better 40 retain the tight-rope within the braking device the face of the brake block or that of the V-groove may be made concave.

When it is desired to launch an aeroplane fitted by the braking device aforesaid the 45 brake block is brought up initially into its highest position when the V-groove is approximately filled and the lower face of the brake block forms a bridge rendering the runner virtually continuous. The aeroplane 50 may be flown from the track under its own motive power, the coefficient of friction between the runners and the tight-ropes being, comparatively speaking, low. If required, however, launching may be assisted by a cable actuated by a hydraulic cylinder or 55 winding engine in a manner well known.

The multiple tight-rope track aforesaid is preferably arranged on such a level as to be clear of gunfire if the vessel be armed. 60 Aeroplanes may be conveniently brought aboard after landing by means of a derrick

or "scotsman" carried from one of the masts.

In the application to ocean-going vessels it is important that the platform utilized 65 shall be to windward of the ship so that the pilot will not be flying in disturbed air and eddy currents; it is for this reason that it is proposed to provide the platform in duplicate. The system should prove of great ad- 70 vantage from the naval standpoint inasmuch as the aeroplane-carrying ship will be able to launch and receive aeroplanes without deviating from its course and thus where such a ship is accompanying a fleet or 75 convoy, this is a matter of vital consequence since it will be able to keep station. The problem of an aeroplane carrier accompanying a battle fleet or cruiser squadron steaming at from 20 to 30 knots is otherwise one 80 of great difficulty. While maneuvering to windward in order to pick up or launch aeroplanes, the carrier ship as constructed not only cannot keep station, but is unable to keep pace with the squadron to which it is 85 attached.

Having now described my invention, what I claim as new and desire to secure by Letters Patent is:—

1. An aeroplane adapted to alight on a 90 track and provided with a runner designed to engage the track, and brake means located on the runner and operable upon engagement of the runner with the track for clamping the track.

2. An aeroplane adapted to alight on a 95 rope track provided with a runner designed for receiving a rope of the track and brake means for clamping said rope in said runner.

3. An aeroplane adapted to alight on a 100 tight-rope track, provided with a runner having a V-shape groove adapted to receive a rope of the track, and a brake block for clamping a rope in said groove.

4. The combination with a supporting structure, of outriggers pivotally secured to said structure for horizontal swinging movement, a series of vertical shafts rotatably mounted in each of said outriggers 110 and each having a quadrant head provided in its upper face with a groove and a recess and provided between the recess and rear edge with a bore, ropes extending between the outriggers and engaging the grooves 115 and bores, and means adjustably engaged with the ends of each of the ropes and bearing against the heads for adjusting the tension of the ropes.

In testimony whereof I have signed my 120 name to this specification.

FREDERICK WILLIAM LANCHESTER.
